CLAIM

The ornamental design for a multi-function helmet, as shown and described.

DESCRIPTION

FIG. 1 is a front perspective view of a multi-function helmet showing my new design;
FIG. 2 is a rear perspective view thereof;
FIG. 3 is a front elevational view thereof;
FIG. 4 is a rear elevational view thereof;
FIG. 5 is a top view thereof;
FIG. 6 is a bottom view thereof; and,
FIG. 7 is a right side elevational view thereof, the left side being a mirror image.

FIG. 1

FIG. 2

FIG. 7

FIG. 3

FIG. 4

FIG. 5

FIG. 6

UNITED STATES PATENT AND TRADEMARK OFFICE
CERTIFICATE OF CORRECTION

PATENT NO. : Des. 360,058
DATED : July 4, 1995
INVENTOR(S) : John W. Reed

It is certified that error appears in the above-identified patent and that said Letters Patent is hereby corrected as shown below:

On the title page, item [76] Inventor:
The inventor's name should be spelled "John W. Reed".

Signed and Sealed this

Twenty-second Day of August, 1995

Attest:

BRUCE LEHMAN
